US0D1104945S

(12) **United States Design Patent** (10) **Patent No.:** **US D1,104,945 S**
(45) **Date of Patent:** **** Dec. 9, 2025**

(54) **BATTERY**

- (71) Applicant: **Zhuhai CosMX Battery Co., Ltd.**, Zhuhai (CN)
- (72) Inventors: **Desheng Xu**, Zhuhai (CN); **Yongwang Wang**, Zhuhai (CN); **Zhida Wei**, Zhuhai (CN); **Yuxiang Zeng**, Zhuhai (CN); **Hongkai Lin**, Zhuhai (CN); **Longyun Chen**, Zhuhai (CN)
- (73) Assignee: **Zhuhai CosMX Battery Co., Ltd.** (CN)
- (**) Term: **15 Years**
- (21) Appl. No.: **29/799,371**
- (22) Filed: **Jul. 14, 2021**

(30) **Foreign Application Priority Data**

- Feb. 23, 2021 (CN) 202130102789.2
- (51) **LOC (15) Cl.** **13-02**
- (52) **U.S. Cl.**
USPC **D13/103**
- (58) **Field of Classification Search**
USPC D13/103, 110, 118-121, 184, 199
CPC H01M 50/107; H01M 50/109; H01M 50/153; H01M 50/213; H01M 50/216; H01M 50/247; H01M 10/0422; H01M 10/0427; H01M 10/123; H01M 10/124; H01M 2250/30

(57) **CLAIM**

The ornamental design for a battery as shown and described.

DESCRIPTION

FIG. 1 is a perspective view of a battery;
FIG. 2 is a front view of the battery;
FIG. 3 is a rear view of the battery;
FIG. 4 is a left view of the battery;
FIG. 5 is a right view of the battery;
FIG. 6 is a top view of the battery; and,
FIG. 7 is a bottom view of the battery.

1 Claim, 7 Drawing Sheets
